F. E. SEELEY

GAS RANGE

Filed Dec. 6, 1923

FIG. 1.

FIG. 2.

FIG. 3.

Inventor

Frank E. Seeley.

By *Custodian Bryant Darby*
Attorney

UNITED STATES PATENT OFFICE.

FRANK E. SEELEY, OF PORT CHESTER, NEW YORK, ASSIGNOR TO ABENDROTH BROTHERS, OF PORT CHESTER, NEW YORK, A CORPORATION OF NEW YORK.

GAS RANGE.

Application filed December 6, 1923. Serial No. 678,921.

To all whom it may concern:

Be it known that I, FRANK E. SEELEY, a citizen of the United States, residing at Port Chester, in the county of Westchester and State of New York, have invented new and useful Improvements in Gas Ranges, of which the following is a specification.

The present invention relates to improvements in gas ranges, and particularly to ranges of the type in which a substantially solid top or cover is provided above the burners.

With such "closed top" gas ranges, which are now coming into quite extensive use, considerable difficulty is experienced in insuring the proper direction of the flame from each burner upward about the lower end of a vessel or receptacle placed in a hole or aperture in the top above the burner. Also it is found that where a plurality of burners are provided, the flame of those near the rear of the stove is frequently deflected laterally by the rearwardly moving current of the products of combustion from a front burner or burners.

The particular objects of the present invention are to provide a simple but very effective means for directing the flame of each burner of a gas range upward and protecting it from being affected by the action of another burner or burners or the current of products of combustion therefrom.

With these and other objects in view the invention resides in the particular construction and arrangement of parts that will be hereinafter pointed out and claimed.

It is to be understood that in the accompanying drawing some of the parts are shown more or less conventionally and there can, of course, be considerable variation in the details of construction shown without departing from the invention.

In the accompanying drawings:

Figure 1 is a plan of a gas range embodying the present invention, a portion of the top plate being broken away above one of the burners.

Figure 2 is a transverse vertical section, on a slightly enlarged scale.

Figure 3 is a detail, sectional view, of a slight modification of the embodiment illustrated in Figure 2.

Referring to the drawing, in which like reference characters designate corresponding parts in the several views, 1 designates

a portion of the frame of a gas range, and 2 designates the top or cover plate which is mounted on said frame over the burners 3.

The frame may, of course, be of any suitable size and form, including either elevated ovens or oven chambers arranged below the top 2 and the latter is, as usual, provided with a plurality of openings or apertures, one above each burner, adapted to receive a cooking vessel or utensil.

In the embodiment of the invention illustrated the top plate 2 is provided with an integral marginal skirt or flange 4 that extends downward and forms a substantially vertical wall extending around the space in which the burners 3 are supported.

The lower edge of the marginal flange 4 of the top is preferably in substantially the horizontal plane of the main gas supply pipe 5, and the branch pipes 6 connecting the main supply pipe 5 with each of the burners 3 extend through mixing valves 7 that are embraced by recesses formed in the lower edge of said flange. A suitable cut-off valve 8 is provided for each burner pipe 6 in the ordinary manner.

As shown, a grid or apertured support 9 is arranged within each of the utensil receiving openings in the top plate, and such openings are closed by imperforate plates 10. These features, however, do not constitute a part of the present invention, and, therefore, are not described more in detail herein.

As shown in Figure 1, the forward burners and the cooperating utensil receiving apertures or openings in the top plate 2 are considerably larger than the corresponding burners and openings in rear thereof. It will also be noted that the centers of the burners and said openings in the top plate 2 are not in the same plane or line extending from the front to the rear of the stove. That is, the smaller, rearward, burners and apertures are offset laterally from the lines including the centers of the front burners and openings. This arrangement provides a passage for the products of combustion from the forward burners to the outlet 10 of the burner chamber, which passage is of greater width at its rear end than between the forward burners. Therefore, the currents of the products of combustion from the front burners to said outlet 10 will not affect the flame of the rear burners to the

same extent that they would if the said rear burners were in substantially longitudinal alignment with the front burners.

Additional means hereinafter referred to are also provided for preventing the currents of the products of combustion from the front burners interfering with or affecting the flame of either of the rear burners.

As shown, each of the burners consists of a suitable body, shaped, as usual, to provide a series of radially projecting arms having perforation in their upper faces, although there can be variations in the designs of this burner without departing from this invention. Each burner is provided with an upwardly extending guard or stack 11. The guard 11, as shown, has at its upper end an outwardly projecting flange 12, which extends laterally beyond the body of the burner. The guard may be of cast metal or any other suitable material, and of any suitable form. As shown, it extends continuously around the burner and forms a short stack extending above the burner openings so that the flame and products of combustion from the burner will be initially directed upward. The walls of the guard 11, 12, extending above and outwardly from the burner openings prevent the flame of the burner from being seriously affected by moving drafts or currents through the space or chamber in which the burners are arranged and thus aid in insuring perfect combustion of the mixture being burned.

Instead of providing each burner with a separable guard 11, the burner body itself may have an integral upwardly extending marginal flange 13 terminating at its upper end in a lateral extension 14, as shown in Figure 3.

Preferably, although not necessarily, the guard 11 extends completely about the burner. Some of the advantages of the invention, however, may be obtained if such guard extends but partially about the

burner, the location thereof being determined according to the direction from which objectionable drafts or currents are likely to approach the burner.

I claim:

1. In a gas stove, the combination with a burner chamber having an outlet for products of combustion, of a top plate covering said chamber and provided with four apertures, each adapted to receive a cooking utensil, all situated in transverse planes between said outlet and the front edge of the plate and arranged in two pairs positioned, respectively, adjacent the front edge of the plate and rearward thereof, and a burner below each said aperture, the members of the rear pair of apertures and the burners in alignment therewith being of smaller diameter than the apertures and burners of the forward pair and the centers of the rear pair of apertures and burners being spaced laterally a greater distance than the centers of the forward pair, whereby the flow of products of combustion from the forward pair of burners to the outlet is not obstructed by the rear burners.

2. In a gas stove, the combination of a top plate provided with four apertures, each adapted to receive a cooking utensil, arranged in two pairs positioned, respectively, adjacent the front edge of the plate and rearward thereof, and having an outlet for products of combustion adjacent its rear edge, and a burner below each said aperture, the members of the rear pair of apertures and the burners in alignment therewith being laterally separated to a greater extent than the members of the forward pair of apertures and their burners, whereby the flow of products of combustion from the front burners to the outlet is not obstructed by the rear burners.

In testimony whereof I have hereunto set my hand.

FRANK E. SEELEY.
